UNITED STATES PATENT OFFICE.

GEORGE HUTCHINSON, OF MASTERTON, NEW ZEALAND, ASSIGNOR TO DONALD HUTCHINSON PATENTS LIMITED, OF MASTERTON, NEW ZEALAND.

FASTENER FOR FENCING WIRES.

1,213,201.

Specification of Letters Patent. Patented Jan. 23, 1917.

Application filed December 20, 1913. Serial No. 807,970.

To all whom it may concern:

Be it known that I, GEORGE HUTCHINSON, a citizen of the Dominion of New Zealand, and residing at Masterton, in the Provincial District of Wellington, in the Dominion of New Zealand, engineer, have invented certain new and useful Improvements in Fasteners for Fencing-Wires, of which the following is a specification.

10 This invention relates to fasteners used for securing wires to fencing posts and dropers and more particularly to fencing posts and dropers made of sheet metal.

15 The invention is illustrated in the accompanying drawing.

Figure 1, is a part sectional elevation, and Fig. 2, a part front elevation of a post fitted with the fasteners; Fig. 3, is a sectional plan on line A—A Fig. 2, Fig. 4, is a part sectional elevation, and Fig. 5, a part sectional plan of a modification, Fig. 6, a part sectional elevation showing the fastener made of wire, Fig. 7, an elevation of a metal plate ready to be bent to form a fastener, Fig. 8, 20 a perspective view of a fastener, Figs. 9, and 10, perspective views of modified forms of wire fasteners.

A post 1 made to take the fastener has holes 2 spaced at regular intervals apart.

30 The fastener 3 consists of a bracket made of sheet metal folded to fit upon the post 1, and has a gap 4 adapted to receive a fencing wire 5. The post 1 has a plurality of holes 2 near its edge and holes 6 in the fastener correspond to the holes 2, in such a way that the holes 6 may be placed to register with any two adjacent holes 2. The gap 4 has a vertical distance from one of the holes 6 equal to one fourth of the distance between 35 the said holes 6. When the fastener is reversed, the gap 4 is raised or lowered a distance equal to one half of the distance between the said holes 6. The number of holes 2 would have to be doubled, if the fastener 40 was not made reversible in the above manner.

The fastener is secured to the post by a keeper 7 which consists of a length of wire having members 8 and 9, passing through 50 the holes 2 and 6 and united by a vertical member 10. The member 9 is extended and bent down to retain the keeper in position.

The fencing wires 5 are held in the gaps 4 by a keeper pin 11, which closes the gaps and 55 may be a single long pin with a loop 12 at

the top, as shown in Figs. 1 and 2, or a staple 13 as shown in Figs. 4 and 5.

Fig. 6 shows the reversible fastener made of wire 14 the spacing 15 in relation to the holes 16 corresponding to the spacing of the 60 gap 4 in relation to the holes 2.

The fastener 17 shown in Figs. 7 and 8 is made from a sheet of metal wherein a hole 18 is punched and nicks 19 and 20 are cut. The metal 21 between the hole 18 and the 65 nicks 20 above and below the nick 19 are bent outward to form lugs prior to the folding of the fastener to fit upon the post, and as shown in Fig. 8. The lugs 21 form a wide contact surface for the fencing wire 5. 70

If it is not desired to make the fastener reversible then the fastener is made with a central gap 22, as shown in Fig. 1.

Fig. 9 shows a reversible fastener made of wire and with a gap 24 corresponding to the 75 gaps 4 and 22 for the reception of the fencing wire 5. The legs 25 and 26 pass through the holes 2 and are bent around the edge of the post 1. Loops 27 and 28 are formed upon the legs for the reception of the keeper pin 80 11, and the said loops are united by a vertical member 30. The leg 26 is longer than the leg 25 thereby throwing the gap 24 into a position relative to the holes 2 as described in regard to gap 4. 85

Fig. 10 shows a reversible wire fastener having legs 34 and 35 bent to form loops 36 and 37 for the reception of the keeper pin 11, and a loop 38 uniting the loops 36 and 37 and forming a gap 40 for the reception 90 of the fencing wire 5.

What I do claim and desire to secure by Letters Patent of the United States is:—

1. A fastener for fence wires, comprising in combination with a fence post, a bracket 95 having a wire receiving slot, means for securing the bracket to the post, and lugs projecting laterally from the slot both above and below the wire to form contact bases wider than the bracket. 100

2. A fastener for fence wires, comprising in combination with a fence post having an approximately vertical web, a bracket made of sheet metal folded over said web and having holes registering with holes in 105 the web, the bracket having a portion adapted to receive a fence wire, and a staple having prongs projecting through the holes in the web and bracket, one of the prongs being offset at its projecting end. 110

3. A fastener for fence wires, comprising in combination with a fence post having an approximately vertical web, a bracket made of sheet metal folded over said web and having holes registering with holes in the web, the bracket having a portion adapted to receive a fence wire, a staple having prongs projecting through the holes in the web and bracket, one of the prongs being offset at its projecting end, and a key for holding the wire in the bracket.

4. A fastener for fence wires comprising in combination with a fence post a bracket having a horizontal slot so as to receive and support a fence wire, and means for attach-

ing the bracket at two points to the post, said horizontal slot being located in such a position relatively to the points of attachment that, by reversing the bracket upon the post, the fence wire holding portion is raised or lowered a distance equal to one half the distance between said two points of attachment. 29

In testimony whereof I have signed my name to this specification in the presence of two witnesses.

GEORGE HUTCHINSON.
